NOZZLE HEIGHT ADJUSTING MECHANISM
FOR VACUUM CLEANERSEdgar P. Turner, Fanwood, N. J., assignor to The
Singer Manufacturing Company, Elizabeth,
N. J., a corporation of New Jersey

Application September 8, 1948, Serial No. 48,194

11 Claims. (Cl. 280—44)

1

This invention relates to ambulatory type vacuum cleaners and more particularly to a nozzle height adjusting mechanism for such a cleaner, whereby a single vacuum cleaner can be used for cleaning a floor regardless of whether the floor is covered with a rug having a thick or a relatively thin pile.

It is well known that the weight of a vacuum cleaner, when operating on a thick pile rug, causes the wheels of the cleaner to sink into the rug. On the other hand, it is known that the wheels of the same vacuum cleaner will not sink an appreciable distance into a rug of average standard thickness. Unless some form of compensating mechanism is provided for adjusting the relative distance between the bottom of the wheels and the nozzle of the vacuum cleaner, the height of the nozzle above the surface being cleaned will be a variable, depending on whether the vacuum cleaner is used on a thick pile rug or on a rug of standard thickness. This problem has been recognized and many mechanisms have been devised to remedy the difficulty. One such mechanism, is disclosed in the expired Brachhausen Patent No. 1,405,095, wherein a pair of front wheels are rotatably carried on a front axle which is supported from the frame of the vacuum cleaners by off-set eccentric members secured to the axle. The Brachhausen patent also provides means located on the lower side of the cleaner by which the front axles can be restrained from rotational movement on the offset eccentrics. However, most of the mechanisms heretofore used have been complicated in design, expensive to manufacture, and difficult to install. Therefore, one of the primary objects of this invention is to provide an improved, simplified, and inexpensive nozzle height adjusting mechanism for vacuum cleaners.

Another object of the invention is to provide a nozzle height adjustment mechanism that can be attached to and remove from a vacuum cleaner without complicated tools and with the least amount of effort.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings:

Fig. 1 is a side elevational view of a vacuum

2

cleaner embodying the mechanism of this invention;

Fig. 2 is an enlarged fragmentary bottom view showing means for mounting the front wheels of the vacuum cleaner illustrated in Fig. 1;

Fig. 3 is an enlarged view in elevation and partly in section, showing one end of the axle support; the section being taken substantially on the line 3—3 of Fig. 1.

10 Fig. 4 is a slightly enlarged fragmentary view in side elevation and partly in section, showing the vacuum cleaner adjusted for operation on a rug of standard thickness, and showing the manner of applying one of the axle holding clips; and

15 Fig. 5 is a view similar to Fig. 4 but showing the vacuum cleaner adjusted for operation on a thick pile rug.

Referring more specifically to the drawings, 20 the invention is disclosed as comprising a vacuum cleaner having a lower casing shell 11 and an upper casing shell 12, the shells being held together by a latch means not shown. The lower shell 11 has a down-facing open mouth 13 through which a lower portion of a rotary brush 14 protrudes. The lower shell 11 also carries a rubber bumper 16 and has a means, later to be described, for rotatably supporting a pair of front wheels 17—17. A combination motor and fan 25 unit, indicated generally by the designation 19, is carried by the two casing shells 11 and 12, and a propelling and pick-up handle 21 is pivotally attached to the motor-fan unit 19 in a manner fully disclosed in my patent application Serial No. 784,167, filed November 5, 1947. The motor-fan unit 19 has formed integral therewith a rearwardly extending exhaust duct 22, to the rear end of which a dust bag 23 is connected by any known means. The upper end of the 30 dust bag 23 is supported from the handle 21 in a manner not shown. Bearing bosses 24, formed integral with the lowermost wall of the duct 22 rotatably supports a pair of rear wheels 26.

40 The means for rotatably and adjustably supporting the front wheels 17—17 from the lower casing shell 11, comprises a pair of spaced bosses or blocks 27—27 formed on the under side of the lower shell 11 and extending inwardly toward one another. Each boss 27 has a horizontally extending and downwardly-facing engagement surface 28, and each boss 27 has a depending front lug 31 and a depending rear lug 32. When viewed from the side, or in other words transversally of the vacuum cleaner (Figs. 45 31, 4 and 5), the lugs 31—32 and the surface 28

define a downwardly open pocket 33, and, when viewed from the front of the cleaner (Fig. 3), the lug 31 in combination with a recessed body portion 35 of the boss 27, defines a downwardly open pocket 34f. When viewed from the rear of the vacuum cleaner, the lug 32, in combination with the body portion 35 defines a downwardly open pocket 34r. The upper surfaces of each boss 27 is provided with an upfacing recess or pocket 36.

A cylindrical axle 37 extends between the two bosses 27—27, and both end portions 38 of this axle are slabbed so that the extreme ends of the axle portions 38 are semi-cylindrical in form. These slabbed or semi-cylindrical ends 38 are disposed in the hereinbefore described pockets 33 and are located in such a manner that either the diametrical portion or the curved portion of the semi-cylindrical ends 38 can be made to engage the surfaces 28. The semi-cylindrical ends 38 of the axle 37 are held against the respective engagement-surfaces 28 by a U-shaped spring wire clip 39. The clip 39 is held in position by having its upper leg 41 located in the pocket 36 and by having its lower leg 42 positioned in the pockets 34f and 34r. The end of each of the legs 41 and 42 is bent into a hook 43 by which the clips are retained on the bosses 27.

A central portion of the axle 37 has a radially extending handle 44 secured to it, as by soldering. As seen in Fig. 2, this handle 44 is stamped with the word "Thick" and also with the designation "Std," which is an abbreviation for the word Standard. These words refer to the two types of carpets which are normally cleaned with the vacuum cleaner of this invention. The wheels 17—17 are rotatably mounted toward opposite terminals of the axle 37, and are held against axial movement along the shaft by punch ears 46 on the axle and washers 47.

Reference to Fig. 4 shows that the top of the open pocket 34r is designated by the numeral 48, and that the top of the pocket 34f is designated as 49. The top 49 is substantially horizontal, whereas, the top 48 is inclined at an angle of substantially forty-five degrees (45°) to the horizontal, the slope being inclined upwardly from the rear of the cleaner. The upwardly sloping top 48 serves two functions. In the first place, it provides means whereby the clip 39 can be attached to the boss 27. In the second place, the sloping top 48 helps to retain the clip on the boss once it has been installed thereon.

The nozzle height adjusting mechanism of this invention is applied to the vacuum cleaner in the following manner. First washers 47—47 and then wheels 17—17 are slipped upon opposite terminals of the axle 37. Then, with the lower casing shell 11 inverted as shown in Fig. 2, the semi-cylindrical ends 38—38 of the axle 37 are placed into the pockets 33—33 in such a manner that the ends 38 rest upon the engagement surfaces 28—28. Then one of the spring wire clips 39—39 is slipped over each boss 27 so that the leg 41—41 of the clips are in the pocket 36—36 and so that the legs 42—42 of the clips are in the pockets 34f—34r. The nozzle height adjusting mechanism of this invention may be assembled with the shaft 37 and ends 38 in either the "Std" or in the "Thick" position. If during the operation of the vacuum cleaner, it becomes desirable to change the setting from "Std" to "Thick" or vice versa, this change can be made by turning the vacuum cleaner upside down and, with the finger flipping the handle 44 so that either "Std"

or "Thick" is visible. When the abbreviation "Std" is seen (solid lines in Fig. 2), the diametrical surface of the semi-cylindrical ends 38 engages the surfaces 28 (Fig. 4), and when the cleaner is resting in cleaning position with the wheels 17—26 on a standard rug, the nozzle opening 13 will be positioned an optimum distance above the surface of the rug. On the other hand, when the word "Thick" is seen (dotted portion 10 of Fig. 2) the curved surface of the semi-cylindrical ends 38 will engage the surfaces 28 (Fig. 5) and then when the cleaner wheels 17—26 rest on a thick rug, the nozzle opening 13 will be positioned an optimum distance above the surface of the thick pile rug. This is because the wheels 17 will have sunk into the thick rug a sufficient amount to lower the nozzle to the optimum distance above the rug.

The spring clips 39—39 perform two functions. 20 In the first place, they hold the axle 37 to the bottom of the cleaner, and in the second place, they retain the nozzle height adjusting mechanism in either of its two adjusted positions. If the mechanism is adjusted for a standard rug, 25 the clips prevent the axle 37 from turning by holding the slabbed surfaces of the ends 38—38 against the engagement surfaces 28—28. If the mechanism is adjusted for a thick pile rug, the clips 39—39 engage the slabbed surfaces of the ends 38—38 and thus prevent the axle from turning.

If one of the clips 39 is to be installed on one of the bosses 27, one of the hooked ends of the clip is placed against the inclined surface 48 (Fig. 4) and the other hooked end is placed against the outer surface of the boss 27. The portion of the boss 27, which is bounded on one side by the surface 48, acts as a wedge to separate the clip sufficiently so that it will easily pass on to the boss 27.

Having thus set forth the nature of the invention, what I claim herein is:

1. In a vacuum cleaner wheel attaching means comprising a pair of spaced horizontally extending bosses formed on said vacuum cleaner, said bosses providing a set of upper surfaces and a set of lower surfaces, a wheel-supporting horizontal shaft having opposite ends adjacent said one set of said boss surfaces, and a pair of U-shaped spring clips providing a set of arms, one set of said arms engaging one set of said surfaces and the other set of said arms holding said shaft adjacent said other set of surfaces.

2. In a vacuum cleaner, a wheel supporting mechanism, comprising, a pair of spaced bosses each having a pocket, a shaft extending between said spaced bosses, and a U-shaped spring clip entering each of said pockets and holding said shaft to said bosses.

3. In a vacuum cleaner, a nozzle height adjusting mechanism, comprising; a pair of spaced bosses each having a pocket formed on its upper side and on its lower side, a shaft extending between said spaced bosses, and a U-shaped spring clip for each of said bosses, said clip entering said pockets and holding said shaft to said bosses.

4. In a vacuum cleaner, a nozzle height adjusting mechanism, comprising a pair of engagement surfaces formed on said vacuum cleaner, an axle, a semi-cylindrical portion on each end of said axles, a wheel rotatably carried on said axle, a pair of spring clips arranged to hold said semi-cylindrical ends of said shaft to said engagement surfaces, and a handle for turning said axle.

5. In a vacuum cleaner having a casing, a nozzle height adjusting mechanism, comprising, a pair of horizontally extending downwardly facing engagement surfaces formed on spaced portions of said casing, an axle having its opposite ends slabbed so as to be substantially semi-cylindrical in cross section, at least one wheel rotatably carried on said axle, a pair of U-shaped spring clips arranged to hold said semi-cylindrical ends of said shaft to said engagement surfaces, and a handle for turning said axle.

6. In a vacuum cleaner, a wheel support and nozzle height adjusting mechanism, comprising, a pair of spaced bosses formed on a lower portion of said vacuum cleaner, a horizontally extending downwardly facing engagement surface formed on each of said bosses, a pair of lugs formed on each of said bosses and extending downwardly from said engagement surface, an axle having its opposite ends slabbed so as to be substantially semi-cylindrical in cross section, a pair of wheel rotatably carried on said axle, a radially positioned index arm secured to a central portion of said axle, and a pair of U-shaped spring clips arranged to hold said semi-cylindrical ends of said shaft to said engagement surfaces.

7. In a vacuum cleaner, a combination wheel support and nozzle height adjusting mechanism, comprising, a pair of spaced bosses having a pocket formed on the upper side of each of said bosses, and having a pocket formed on the lower side of each of said bosses, a shaft having its opposite ends slabbed and arranged to enter the pockets on the lower side of said bosses, a U-shaped spring clip entering the pockets on the upper side of said bosses and holding said slabbed ends of said shaft to said bosses, and wheels rotatably carried on said shaft.

8. In a vacuum cleaner, a nozzle height adjusting mechanism, comprising a pair of spaced bosses having pockets formed on the lower side of each of said bosses, a surface sloping at an angle of approximately forty-five degrees to the horizontal, and positioned to bound an upper boundary of at least one of said pockets, a shaft extending between said bosses, and a spring clip arranged to engage at least one of said sloping

surfaces when being installed on said bosses and arranged to hold said shaft in position when fully clipped on said bosses.

9. In a vacuum cleaner, a wheel support and nozzle height adjusting mechanism, comprising; a pair of spaced bosses having pockets formed on opposite sides of each of said bosses; a surface, sloping at an angle of approximately forty-five degrees to the horizontal, and positioned to bound a portion of some of said pockets; a shaft extending between said bosses; a U-shaped spring clip arranged to engage said sloping surface when said clip is being installed, said clip being arranged to hold said shaft in position when it is fully installed on said bosses; and wheels rotatably carried on said axle.

10. In a vacuum cleaner, a wheel-supporting mechanism, comprising, a horizontally extending boss providing a first surface and a second surface, a wheel-supporting horizontal shaft having a portion adjacent said first surface, and a U-shaped spring clip providing a set of legs, one of said legs engaging said second surface, and the other of said legs holding said portion of said shaft to said first surface.

11. In a vacuum cleaner, a wheel-supporting mechanism, comprising, a horizontally extending boss providing a downfacing surface and an upfacing surface, a wheel-supporting horizontal shaft having a portion adjacent said downfacing surface, and a U-shaped spring clip providing a set of legs, one of said legs engaging said upfacing surface, and the other of said legs holding said portion of said shaft against said downfacing surface.
